UNITED STATES PATENT OFFICE.

ABRAHAM H. GREENEBAUM, OF BALTIMORE, MARYLAND, ASSIGNOR TO ALMA MANUFACTURING COMPANY OF BALTIMORE CITY, OF BALTIMORE, MARYLAND, A CORPORATION OF MARYLAND.

SLIDING-TONGUE BOX-BUCKLE.

1,072,714.

specification of Letters Patent. Patented Sept. 9, 1913.

Application filed March 26, 1913. Serial No. 757,030.

To all whom it may concern:

Be it known that I, ABRAHAM H. GREENEBAUM, a citizen of the United States, residing at Baltimore, in the State of Maryland, have invented a certain new and useful Improvement in Sliding-Tongue Box-Buckles, of which the following is a full, clear, and exact description.

This invention relates to so-called box-buckles with sliding tongues, especially designed for use on belts.

The object of the invention is to simplify the construction of the frame part and the tongue part of such box-buckles, and render the action more positive and secure.

Where apparel straps or belts are furnished to dealers with the strap sewed or riveted or otherwise permanently fastened to the buckle, it is necessary for the dealer to carry a considerable stock of straps or belts of different lengths, or else mutilate the strap or belt, or destroy its permanent attachment in order to re-attach it so that the purchaser may obtain a strap or belt of the desired length. Obviously, if dealers could be supplied with straps not permanently attached to the buckle, or so attached as to be readily detached, then a customer having selected a strap or belt and finding it too long, the dealer could readily detach the strap or belt and cut it off to the proper length and then readily apply it again to the buckle. In such case it would only be necessary for the dealer to supply himself with straps or belts of maximum or maximum and minimum length, and yet be in position to accommodate the large majority of customers. The buckle of the present invention admits of this convenience. The straps or belts are also made of different thickness, and the means for attaching the strap or belt to the buckle should be of such character as to admit of the attachment of such straps or belts of any thickness from maximum to minimum. This invention is designed to meet this contingency also.

The ready operation of the sliding tongue, the facility with which the free end of the strap or belt may be adjusted in the buckle, and the security of the engagement of the sliding tongue with the free end of the strap or belt are of equal importance, and these features are also elements of the invention.

The invention, therefore, consists of a sliding tongue box-buckle, having a clamping

lever for securing the attached end of the strap or belt, and such lever may be adjustable so as to admit of the use of belts of different thickness; and a sliding tongue co-operating with a wedge element to engage the free end of the strap or belt to secure it adjustably in place when the strap or belt is applied to the person, all as I will proceed now to explain and finally claim.

In the accompanying drawings illustrating the invention, in the several figures of which like parts are similarly designated, Figure 1 is a plan view with strap ends in fastened position. Fig. 2 is a side elevation and Fig. 3 is a bottom plan view of the buckle detached. Fig. 4 is a horizontal section, taken just beneath the face-plate of the buckle. Fig. 5 is a longitudinal section, with the parts in position to receive the free end of the strap. Fig. 6 is a cross-section taken substantially in the plane of line A-B, Fig. 2, and looking toward the right. Fig. 7 is a longitudinal section showing the strap ends in engaged position as in Fig. 1. Fig. 8 is a cross-section substantially in the plane of line C-D, Fig. 7, looking toward the left. Fig. 9 is a side elevation, showing the clamping lever adjustment or compensation feature, and omitting other features.

The buckle comprises a base-piece 1, which may be made of sheet metal, having a depressed portion 2 from which rises ears 3 at substantially right angles thereto and in which ears is journaled a clamping lever 4, of any approved construction, and so arranged that when a strap or belt end as 5 is placed between the portion 2 and the clamping lever 4 and said lever turned down, as in Figs. 2, 5 and 7, the strap or belt end will be securely attached to the buckle, and may be readily removed therefrom by lifting the lever. Thus, while the strap end is firmly secured to the buckle, it is not necessary to use stitches or rivets or other permanent attaching means, and the belt may be readily detached from the buckle and cut off so as to obtain any length of belt required by the customer, and the belt then re-attached.

In order to accommodate belts or straps of different thickness, the ears 3 may be provided with a connected series of bearings for the lever, as shown at 6 in Fig. 9, so that the lever clamp may be shifted from one to another of these bearings in accordance

with the thickness of the strap that is to be attached.

The portion 2 is depressed so that when the free end of the strap or belt is secured to the buckle, it may rest on top of the lever without undue protuberance. Thus a dealer may carry in stock straps or belts of two or three different lengths and thicknesses and yet be able to accommodate a great variety of customers.

The bottom or base plate 1, is provided with a wedge-like projection 7, rising toward the free end of the buckle and ending abruptly at or near the transverse center of the box portion. If the buckle be made of sheet-metal, this wedge 7 (so herein designated) may be pressed to shape. The wedge is not only of less length than the buckle but also is of less width, as seen in Figs. 3, 4 and 8.

The cover or loop 8 is three-sided, and more or less ornamental, and it may be conveniently attached to the bottom by a number of ears 9 engaging notches 10 in the edges of the bottom and bent over flat upon the bottom, as shown in Figs. 3 and 5 to 8.

The sliding tongue 11 is a flat plate, of sheet metal or other material, having a central hole 12 to fit over or straddle the wedge 7, and provided with an upright member 13 transversely arranged at its inner or rear end. This upright member may be toothed, as shown, or it may be otherwise formed, so as to grip the free or adjustable end 14 of the strap or belt between itself and the adjacent inner surface of the box, loop or cover 8 when said tongue is drawn up upon the wedge, as in Figs. 7 and 8. In order to manipulate the tongue for fastening and releasing the strap, said tongue is made with the lateral projections 15, which extend through slots 16 in the sides of the cover and are turned up alongside these sides, thus affording finger-holds for the tongue and also serving in connection with the slots as means for retaining the tongue in the buckle.

To fasten the strap end, the tongue is slid back, as in Fig. 5, so as to remove its upright out of the path of said end, and then when the required adjustment is reached, the tongue is slid forward, as in Figs. 7 and 8, so as to cause the inner end of the tongue to ride up upon the wedge and thereby bring the upright 13 into engagement with the strap end and clamp or grip it between said upright and the adjacent inner surface of the top of the cover 8. The strains of use will tend to further draw the tongue up the rising wedge and increase its hold upon the strap. Relaxation of the holding strain will permit the tongue to be slid back by a backward drawing on its projections 15.

Thus a very simple and efficient sliding tongue box-buckle is provided.

Variations in details of structure and arrangement are contemplated as within the principle of the invention.

What I claim is:

1. A sliding tongue box-buckle, having a wedge in its bottom, and a tongue provided with a central opening and straddling the wedge and having an inner end sliding upon said wedge to engage and release the strap end.

2. A sliding tongue box-buckle, provided with a strap attaching medium, and having a bottom provided with a wedge rising therefrom, and a tongue straddling said wedge and provided with an upright to 80 engage the adjustable end of the strap.

3. A sliding tongue box-buckle, having a bottom provided with a wedge rising therefrom, and a tongue straddling said wedge and provided with an upright to engage 85 the strap end and also having operating projections extending outside of the buckle.

4. A sliding tongue box-buckle, having a bottom provided with a wedge rising therefrom, and a tongue straddling said wedge 90 and provided with an upright to engage the strap end and also having operating projections extending outside of the buckle and engaging the buckle so as to retain the tongue in the buckle.

5. A sliding tongue box-buckle, comprising a base plate having strap attaching means, a wedge rising forwardly on said base plate, a loop or box-like cover applied to said base plate over the wedge, and a 100 sliding tongue provided with a central opening to fit over said wedge and having a strap-engaging upright adapted to be rendered effective to engage and release such strap by moving up and down said wedge.

6. A sliding tongue box-buckle, comprising a base plate having strap attaching means, a wedge rising forwardly on said base plate, a loop or box-like cover applied to said base plate over the wedge, and a sliding tongue provided with a central opening to fit over said wedge and having a strap-engaging upright adapted to be rendered effective to engage and release such strap by moving up and down said wedge, and having projections extending outside of said cover for effecting the movement of said tongue.

In testimony whereof I have hereunto set my hand this 25th day of March, A. D. 120 1913.

ABRAHAM H. GREENBAUM.
